UNITED STATES PATENT OFFICE.

JOHN L. BARNES, OF LOS ANGELES, CALIFORNIA.

DE- AND RE-CAPPER FOR SHOTGUN-SHELLS.

1,269,249.

Specification of Letters Patent. Patented June 11, 1918.

Application filed May 1, 1917. Serial No. 165,789.

To all whom it may concern:

Be it known that I, JOHN L. BARNES, a citizen of the United States, residing at Los Angeles, in the county of Los Angeles and State of California, have invented a new and useful De- and Re-Capper for Shotgun-Shells, of which the following is a specification.

This invention relates to an interconvertible device adapted to be easily changed by interchange and readjustment of parts, so as to perform the operations of removing from exploded shells the used primers and replacing them with new primers; and also adapted to be changed by the use of interchangeable parts so as to operate on shells of different sizes and to displace and to insert into place primers of different sizes.

Objects of this invention are strength, cheapness and simplicity of construction, convenience and ease of adjusting and removing the shells, ease and convenience of handling and operating the device, and ease, accuracy and speed in the operation of de-capping and re-capping the shells.

The invention may be carried out in various forms.

An object is to provide a compact device of this character that can be readily taken apart and packed in small space and which will consist of strong parts, only a few of which need be detached at any time when the tool is in set up operable condition.

Another object is to provide strong and convenient means for rigid attachment of the operative means to a support.

Other objects and advantages may appear from the accompanying drawings, the subjoined detail description and the appended claims.

The accompanying drawings illustrate the invention.

Figure 1 is a view partly in section of the novel de-capping and re-capping device with parts in position to remove a primer from a shell which is shown in place. Dot-and-dash lines indicate the position of the shell and the de-capping plunger when the primer has been removed. A detached re-priming tool and a set of interchangeable parts of a different size are also shown.

Fig. 2 is an elevation mainly in vertical axial section showing the device as a re-primer in use seating a primer in a shell.

The set screws are displaced from the position shown in Fig. 1, for clearness and convenience of illustration.

Figs. 3 and 4 are broken views partly in section showing the machine supplied with the larger tools adjusted respectively for de-capping and re-capping where larger primers are used.

Referring to Fig. 1 the stake comprises a socketed body 1 and a punch 2 seated in the socket 3 in the top of said body, and held therein by a set-screw 4, said punch having an enlarged shank 5 fitting the socket 3 and engaged by the set-screw 4. The tool to co-operate with the stake as arranged for de-capping, comprises the socketed plunger 6; and the tool to co-operate with the punch stake as arranged for re-capping, comprises a pressing plunger 7, the contacting end of which has a shallow concavity *a* conformed to the end of a primer so that the primer may be seated without crushing or distorting the primer.

Oscillating means are provided to control the de-capping and re-capping tools. To this end the radius arm 8 is swiveled on a post 9 eccentric to the stake 1 and is thereby adapted to swing freely about a vertical axis to and from the space above said stake. Said radius arm has jointed connection with the post by means of a swivel member 10 and a horizontal pin 11 so as to swing in a vertical plane on a horizontal axis; said swivel member being positioned on the post 9 by the horizontal pins 12, 13 inserted through the post below and above the swivel member; and said swivel member 10 being provided with lugs 14 between which the end of the radius arm 8 is pivoted by the horizontal pin 11.

Said radius arm carries oscillating means in the form of a tool carrier 15 having a socket 16 therein and having jaws 17 between which the radius arm 8 is pivotally mounted by means of a horizontal pin 18. The shoulder 19 between the jaws 17 serves as a stop against which the arm 8 will impinge when the radius arm is raised as shown in dot-and-dash lines in Fig. 2, provided the plunger socket 16 is in vertical position as shown.

The socketed plunger 6 is provided at its upper end with a shank 20 which fits in the socket 16 of the tool carrier and is engaged

by a set screw 21 that retains the plunger or de-capping tool 6 in place.

The swiveled re-capping tool guide 22 is pivoted by a horizontal pin 23 to the guide 5 swivel 24 which oscillates horizontally on the post 9 and is supported by a transverse pin 25. The re-capping tool guide 22 is provided with a bore 26 at right angles to the pin 23; and a tool guide bushing 27 10 having an axial bore 28 is mounted in said bore 26 and held in place by a set screw 29 in guide 22.

The recapping tool 7 fits in the socket 16 and is interchangeable with the decapping 15 plunger 6; either being adapted to be inserted and held by the set screw 21 when the other is withdrawn from the socket 16.

In practice when it is desired to decap the shell 30 having an exploded primer 31, 20 such shell with its primer seated therein, will be placed over the stake 1 while the punch is in the stake with its pin 2 projecting up in alignment with the primer, and the radius arm 8 will then 25 be swung into position to allow the socket 32 of the de-capping plunger to accommodate the primer when the shell is pressed down by the plunger. Then radius arm 8 will be depressed by handle 33 thereby 30 forcing the socketed plunger 6 and the shell 30 down while the pin 2 of the punch holds the primer 31 stationary. The shell is thus removed from the primer and when this has been effected the handle 33 will be 35 raised and the plunger 6 will thus be withdrawn from the shell, allowing the primer 31 to drop out of the socket 32 which is of larger diameter than the primer.

After a batch of used shells has thus been 40 de-capped the decapping plunger 6 will be detached and the decapping punch will be removed from the stake. In case the stake is provided with the thin bore 34 extending down from the socket 3 in the 45 stake to receive the punch pin 2, the punch may be inverted and re-inserted into the socket. The butt of the punch shank thus closes the socket and will assist to support the end of the shell. In cases where the 50 primers project inside the shell the punch will be left out of the stake for repriming.

It is not necessary to do this except to 55 keep the punch safely; as the stake will support the shell for recapping irrespective of whether the socket 3 is or is not closed.

The tool holder 15 will then be aligned with the bushing 28 and a re-capping plunger 7 will be inserted up through the bushing and into socket 16 where it will be secured 60 by set screw 21.

A bore 46 in the butt of the punch is provided to accommodate the inserted end of the form of primer shown in Figs. 3 and 4.

The base 36 of the device is provided with 65 two upwardly extending collars 37, 38, the axes of which are in parallelism with each other, to hold the stake 1 and post 9 in parallelism with each other. The post is retained in collar 38 by the pin 39 and the 70 stake is reduced at its lower end to fit in the collar 37 and is detachably secured by set screws 40.

The base is provided with holes 41 through which screws 42 may be screwed 75 into a support 43.

When the base is thus secured to a stationary support, and handle 33 is raised, it will draw the pressing plunger 7 up until the lower end is far enough above the 80 lower end of the guide bushing 27 to allow a primer to be inserted into the bore 28 of the tool guide bushing.

A shell 4 will then be placed on the stake as shown in Figs. 2 and 4, and a fresh 85 primer will be inserted into bushing 27 which will then be swung over the shell to bring the primer into position to be seated in the shell.

Then the handle 33 will be depressed until 90 the plunger 7 seats the primer in the shell.

It is thus seen that the respective de-capping and re-capping tools or plungers are controlled respectively at separate times to alternatively coöperate with the convertible punching and non-punching stake 1, 2 and 5, as occasion may require.

The swinging radius arm 8 which is oscillatable upon the vertical axis 9 and the horizontal axis 11 is thus brought into operative relation successively through the medium of the tool carrier 15 and the tool guide 22, both of which are operable by, and are in movable relation to, the radius arm for controlling the tool which coöperates with the stake; thus giving a required flexibility of movement to the parts for effecting either required operation at the time it is to be performed.

It is to be noted that when the recapping 110 plunger is in place as shown in Figs. 2 and 4 and the radius arm 8 is raised, it and the shoulder 19 contact with each other before the plunger 7 can withdraw from the bore 28, and the shoulder thus forms a stop to 115 prevent the handle from being raised too high relative to the stake, and also keeps the plunger from being withdrawn from the bushing. The pins 11, 18, 23, the member 22, tool carrier 15, tool guide 27, and 120 plunger 7 all coöperate to stop the arm 8.

The box of the bushing 27 may have an enlargement 44 to accommodate the enlarged head 45 of a presser plunger 7' for the larger primers 31'.

An enlarged decapping plunger 6' having a socket 32' for the larger primers 31' will go along with the set. Stakes as 1 and 1''

of different diameters are provided to fit shells of different gage. The change from one size to the other is easily made in an obvious manner to fit the device for use on various size shells.

By mounting the swivel member 10 on a vertical axis or post 9 and mounting the rotary arm 8 and the oscillating tool carrier 15 thereon, the movement of the hand 10 in the operation of de-capping or re-capping is minimized as the tool need be removed only the width of the shell to the right or to the left to free the shell, so that it may be withdrawn from the stake. 15 This facilitates the operation, all that is necessary being to shift the handle 33 a very slight distance to the right or left, place the shell on the stake, then return the handle and apply pressure through a very small 20 arc. Then raise the handle and shift it to the right or left as before and then withdraw the shell. These operations are readily performed for either the de-capping or the re-capping operations.

25 I claim:

1. A de- and re-capper comprising a convertible punching and non-punching stake having an end socket, and a punch detachably mounted in said socket; interchangeable tools comprising a socketed plunger of one diameter and a pressing plunger of less diameter to coöperate respectively with the stake and its punch when the punch is in place and with the stake when the punch is detached; and radius means adapted to swing on a horizontal axis, and about a vertical axis, to control the plungers respectively at separate times to alternatively coöperate with the

stake when it is supplied with the punch 40 and also when it is divested of the punch.

2. A de- and re-capper comprising a stake and a post in parallelism with each other, a tool to coöperate with the stake, and means swiveled to the post on a vertical 45 axis to control the tool for such coöperation.

3. The combination with a stake and a post and a base to which said stake and post are fixed in upright position in parallelism, of a tool to coöperate with the stake, a member vertically and horizontally oscillatable on the post, a handle pivoted to said member, a tool holder pivoted to the handle and extending toward the stake and a tool carried by the tool holder.

4. A de- and re-capper comprising a stake, a tool to coöperate with the stake, and means oscillating on a horizontal axis and swinging on a vertical axis eccentric to the stake to control the tool to effect such co-operation.

5. A de- and re-capper comprising a base; a post and a stake fixed to the base in parallelism with each other; members swiveled on the post; means pivoted to one 65 of said members and adapted to operate a tool toward and from the stake; and guide means pivotally connected to the other one of said swivel members and adapted to swing over the stake as and for the purpose 70 set forth.

In testimony whereof, I have hereunto set my hand at Los Angeles, California, this 24th day of April, 1917.

JOHN L. BARNES.
